UNITED STATES PATENT OFFICE.

FREDERICK L. SCHLEY, OF BROOKLYN, NEW YORK.

FURNITURE FOR FORMING PAPER-BOX DIES AND FOR USE IN TYPE COMPOSITIONS.

1,344,657.

Specification of Letters Patent. Patented June 29, 1920.

Application filed January 16, 1920. Serial No. 351,798.

To all whom it may concern:

Be it known that I, FREDERICK L. SCHLEY, a citizen of the United States, and resident of the borough of Brooklyn, in the county 5 of Kings, city and State of New York, have invented certain new and useful Improvements in Furniture for Forming Paper-Box Dies and for Use in Type Compositions, of which the following is a specification.

10 The present invention relates to improvements in furniture for forming paper box dies and for use in type compositions, and has for an object to provide such furniture by means of which the dies may be formed 15 in a simple and accurate manner, and which will be of very strong, and at the same time, light construction, and to this end, I propose to provide a metallic furniture of substantially skeleton form. A further object of 20 the invention is to provide a novel and effective releasing means for releasing the paper blank from the die, after it is cut and scored, and more particularly, I propose to provide 25 tapered pockets in spaced relation in the furniture to receive corks, or other suitable yieldable plugs. I further propose to provide 30 a furniture which is reversible, and so constructed at the ends as to be fitted with other furniture to form a sharp and well-defined right-angular corner.

A still further object is to provide such furniture, which, when arranged in a form may be tied with a binding cord in such manner that the cord will not project therefrom. It is also further proposed to provide 35 furniture, which may be used in type compositions to frame the type, or as a "filler" in type forms. To the end of enabling the tying of the furniture by means 40 of a binding cord without projection of the cord, and also the reception of a binding cord about a type form, I propose to provide grooves in the furniture.

With these and other objects in view, an 45 embodiment of my invention is shown in the accompanying drawings, and this embodiment will be hereinafter more fully described with reference thereto, and the invention will be finally pointed out in the 50 claims.

In the accompanying drawings:

Figure 1 is a plan view showing the present embodiment of my improved furniture for cutting and scoring blanks for boxes, 55 the furniture being shown set up in a form.

Fig. 2 is a vertical sectional view taken along the line 2—2 of Fig. 1.

Fig. 3 is a plan view of a type composition, showing the same framed with my improved furniture.

Fig. 4 is a side elevation of one piece of 60 the improved furniture.

Fig. 5 is a top view thereof.

Fig. 6 is a longitudinal sectional view.

Fig. 7 is a cross section taken along the 65 line 7—7 in Fig. 4.

Fig. 8 is a cross section taken along the line 8—8 of Fig. 4.

Similar reference characters indicate corresponding parts throughout the several 70 figures of the drawings.

Referring to the drawings, the furniture, according to the present embodiment of my invention, comprises a strip 10, preferably of metal, having parallel longitudinal upright faces, said strip being straight at one end, and provided at its other end with an angular recess 11. The strip intermediate its ends is of H shape in cross section, having longitudinal recesses extending from its 75 upper and lower faces, and a central lateral web 12. At the ends of the strip and centrally thereof, there are provided tapered pockets 13 and 14, extending from each of the horizontal faces of the strip, the central 80 web 15 forming a bottom for the said pockets. The vertical faces of the strip, with the exception of the angular recess 11, are provided with a longitudinal groove or channel 16, substantially central thereof, 90 and adapted to receive a binding string, either placed around the furniture, or around a type form or other structure, which is engaged by the strip, the strip in the latter case lying flat against the sides of the type to 95 prevent displacement thereof.

The pockets 13 and 14 are adapted to receive tapered corks 17 or other suitable yieldable plugs, for the purpose of releasing the paper from the die after it is cut and 100 scored, and with the corks for this purpose extending slightly above the cutting and scoring blades of the form, and being yieldable. The base 15 firmly supports the corks, while the tapering of the pockets enables 105 the same to be firmly held, and at the same time readily removed when desired. The provision of the pockets at both sides of the furniture enables either side to be uppermost, this being important to permit re- 110

versal of the recessed ends, so that while the strips may be reversed and turned in any desired relation, they will all be of the same form. It will be understood, that the strips 5 may be of any desired length, depending upon the size of the work to be done.

In use, the furniture forms the sides of rectangular portions of the die form, scoring or cutting rules or blades 18, as required, 10 being placed and held between the furniture, as illustraed in Fig. 1, the whole form being then keyed or otherwise locked in a frame 19, by means of wedges 20, and blocks 21, or other like devices. The form is placed in 15 a press, and the sheet from which the blank is to be produced, is laid upon the upper face of the form, and by operation of the press, it is cut and scored. As soon as the blank is relieved from pressure, the releasing corks, 20 which are under compression at that time expand, and force and hold the blank from engagement with the score rules or blades.

The form may be tied by means of a binding cord when it is desired to remove the die 25 from the frame, and hold the parts making it up together, in which case the cord will lie in the recess 16, and will not project beyond the face of the strip, so that the same may be snugly fitted into a frame without 30 removal of the string, or if it is to be stored, it may be placed in a galley, in which case the sides of the furniture will snugly engage the inner sides of the galley, and accidental disarrangement of the pieces will be prevented. 35

The furniture may also be used in type 40 form composition as a frame about a form of type. It is usual to place a binding cord about a form of type, and when the furniture is engaged with the sides of the type, this 45 cord will be pocketed in the groove 16, so that the sides of the type will fit tightly and snugly against the sides of the furniture, and will therefore be held against displacement. In Fig. 3 I have shown this arrangement, the cord 22 about the type 23 being pocketed in the nine recesses 16, while the cord 24 about the frame is pocketed in the outer recesses 16.

50 With my improvements, a die form may be constructed with accuracy and facility, the strips of the desired length being selected and placed in position, the reversibility of the strips permitting their proper 55 placement. When complete, the releasing corks may be placed in the sockets, as re-

quired, without the necessity of hammering them in place, and with comparative ease, due to the tapering of the pockets.

I have illustrated and described a preferred 60 and satisfactory embodiment of my invention, but it is obvious that changes may be made therein within the spirit and scope thereof, as defined in the appended claims. 65

I claim:

1. A furniture of the character described, comprising a strip having one end straight and its other end recessed on its inner face, and provided with pockets adapted to receive yieldable releasing plugs, said pockets 70 extending from each longitudinal face of said strip and provided with a bottom intermediate said faces.

2. A furniture of the character described, comprising a strip having one end straight 75 and its other end recessed on its inner face, and provided with tapered pockets adapted to receive tapered yieldable releasing plugs, said pockets extending from each horizontal face of said strip, and provided with a bot- 80 tom intermediate said faces.

3. A furniture of the character described, comprising a strip having one end straight and its other end recessed on its inner face, and provided with pockets adapted to receive yieldable releasing plugs, said pockets 85 extending from each longitudinal face of said strip and provided with a bottom intermediate said faces, said strip having recesses in its upper and lower faces intermediate said pockets.

4. A furniture of the character described, comprising a strip having one end straight and its other end recessed on its inner face, and provided with pockets adapted to receive yieldable releasing plugs, said pockets 95 extending from each longitudinal face of said strip and provided with a bottom intermediate said faces, said strip having recesses in its upper and lower faces intermediate said pockets, and having a lateral central web forming a bottom for said recesses. 100

5. A furniture of the character described, comprising a strip having one end straight and its other end recessed on its inner face, 105 and provided along its longitudinal sides and ends with a groove adapted to receive a binding cord.

In testimony that I claim the foregoing as my invention, I have signed my name 110 hereunder.

FREDERICK L. SCHLEY.
